(57) **CLAIM**

The ornamental design for a fragrance cartridge, as shown and described.

DESCRIPTION

FIG. 1 is a top perspective view of an embodiment of a fragrance cartridge of our design;

FIG. 2 is a front view thereof;

FIG. 3 is a rear view thereof;

FIG. 4 is a left-side view thereof;

FIG. 5 is a right-side view thereof;

FIG. 6 is a top view thereof; and

FIG. 7 is a bottom view thereof.

FIG. 8 is a top perspective view of another embodiment of a fragrance cartridge of our design;

FIG. 9 is a front view thereof;

FIG. 10 is a rear view thereof;

FIG. 11 is a left-side view thereof;

FIG. 12 is a right-side view thereof;

FIG. 13 is a top view thereof; and,

FIG. 14 is a bottom thereof.

FIGS. 8–14 are illustrated with a symbolic break in the thickness of the fragrance cartridge, represented by break lines. The appearance of any portion of the fragrance cartridge between the break lines forms no part of the claimed subject matter.

1 Claim, 10 Drawing Sheets
